UNITED STATES PATENT OFFICE.

WILLIAM E. ALEXANDER, OF PHILADELPHIA, PENNSYLVANIA, ASSIGNOR
OF ONE-HALF TO JOSEPH C. DANDO, JR., OF SAME PLACE.

INDEX.

SPECIFICATION forming part of Letters Patent No. 653,605, dated July 10, 1900.

Application filed December 8, 1899. Serial No. 739,704. (No model.)

To all whom it may concern:

Be it known that I, WILLIAM E. ALEXANDER, a citizen of the United States, residing in Philadelphia, Pennsylvania, have invented 5 certain Improvements in Indexes, of which the following is a specification.

My invention relates to certain improvements in directories or indexes especially for use in connection with telephones.

10 The object of my invention is to provide an index which can be readily handled with one hand and which will automatically close as soon as released. This object I attain in the following manner, reference being had to 15 the accompanying drawings, in which—

Figure 1 is a perspective view of my improved directory, and Fig. 2 is a sectional view.

A is the casing, made of any suitable material, having a back a, sides a', and a base a'.

B is a cover, pivoted to the base of the case by spring-hinges C C in the present instance, so that the cover can be readily turned down and when released will close automatically.

25 D are a series of cards, each card being stepped, as shown, so as to expose a certain portion of the card above the upper edge of the cover. On the exposed surface of the cards are printed the letters of the alphabet 30 or other indicating-marks. The cards are of such a thickness that they can be handled without crumpling, and they are loose within the case and can be readily removed when it is necessary to add a name to the directory.

35 The cards rest between a block e and the cover B and are kept some distance from the back at their upper edges by a rib or projection f, so that when it is desired to select any one of the cards all that is necessary is to 40 push the finger against the special card, which will force the cards back, so as to allow the finger to enter the space between the card having the desired names and the card in front of it, so that the latter card, together 45 with the cover, can be drawn out to expose the names, as clearly shown in Fig. 1. Thus the edges of the cards are not mutilated or destroyed by constant picking.

It should be observed that the bottom piece 50 e and the rib f are so placed that an inclined rest is formed for the cards, so that the bot-

toms of the cards are held between the cover and the block or piece e at a greater distance from the back of the case than the tops of said cards, and said tops extend above the top 55 piece—that is, the rib f—of the rest, and while I have shown two pieces as composing this rest, as that is a preferable construction, it is obvious that a greater or less number of such pieces may be employed without departing 60 from the essential features of my invention.

The device can be made very cheaply, can be either secured to the wall or rest upon a table, and can be made of wood, metal, or other suitable material. The cards can be 65 made of pasteboard, celluloid, or other suitable material.

While my invention is especially applicable as a directory for telephones, it will be understood that it can be used in convenient 70 form as an address-card for office use or as a memorandum, and in place of the alphabet shown other indicating-marks may be used without departing from my invention.

I claim as my invention—

1. The combination in an index or directory, of a case, a cover hinged to the bottom of the case, an inclined rest at the back of the case, a series of cards mounted within the case confined between the cover-plate and the 80 said rest, with the bottoms of said cards at a greater distance from the back of the case than the tops and the latter extending above the cover-plate and the rest, so that the upper portion of the cards can yield to pressure 85 of the finger, substantially as described.

2. The combination of the case having tapered sides, a cover hinged to the base of the case, springs for closing the cover against the case, a block at the bottom of the case between which and the cover the cards are mounted, and a projecting rib at the back of the case against which the upper portion of the cards rest, the said cards extending above the hinged cover, substantially as described. 90

In testimony whereof I have signed my name to this specification in the presence of two subscribing witnesses.

WILLIAM E. ALEXANDER.
